UNITED STATES PATENT OFFICE.

BENJAMIN EUGENE PARRISH, OF HONEYGROVE, TEXAS, ASSIGNOR OF ONE-HALF TO
DARWIN W. MAURER, OF DALLAS, TEXAS.

PLUG FOR OIL WELLS AND SIMILAR PURPOSES.

Application filed October 30, 1922. Serial No. 597,908.

To all whom it may concern:

Be it known that I, BENJAMIN EUGENE PARRISH, a citizen of the United States, and resident of Honeygrove, in the county of 5 Fannin and State of Texas, have invented certain new and useful Improvements in Plugs for Oil Wells and Similar Purposes, of which the following is a specification.

My invention relates to an appliance or 10 tool adapted to be used as a plug or closure for the casing of an oil, gas or similar well.

The general object of the invention is to provide a simple and economical appliance of the class described, which is provided with 15 effective clutch or gripping means for engaging well casings for retaining the appliance in position therein; to provide a valved passage within the implement, with valve controlling means, so that the valve 20 is held open while the appliance is being lowered to position to permit the free passage through the body of the appliance of fluids, such as oil or gas, and which operates when the plug is properly located in the casing 25 to cause the closing of the valve and of the passage through the implement; and to provide effective means for sealing the small annular space between the body of the implement and the casing, so that in connection 30 with the valve the appliance forms a very tight and effective seal to prevent the escape of liquid or gas.

A further object is to arrange the last 35 named sealing means for cooperation with the valve actuating means so that when the valve closes the exterior sealing means is rendered effective for the purpose above described.

The characteristics and advantages of the 40 invention are further sufficiently described in connection with a detailed description of the accompanying drawing, which shows one exemplifying embodiment of the invention. After considering this, skilled persons will 45 understand that many variations may be made within the principles of the invention, and I contemplate the employment of any structures which are properly within the scope of the appended claims.

50 In the drawings:

Fig. 1 is an exterior view of a complete implement or plug embodying the invention in one form.

Fig. 2 is an enlarged sectional view of 55 the upper portion of the plug.

Fig. 3 is a similar view of the lower portion, these two parts ordinarily being joined at the broken line.

Fig. 4 is a section at 4—4, Fig. 2.

Fig. 5 is a section at 5—5, Fig. 3.

The implement comprises a main or upper portion or body 1, substantially hollow and provided at one point with a valve seat 2. Above the seat is a valve stem guide 3, which may be detachably inserted in the body or, as in the present case, is connected to it by a web or partition 4, provided with a plurality of apertures 5 to permit the passage of gas or liquid. The main structure or shell of the plug is completed by a tubular lower portion 7, screwed into the body at 8. A long valve stem 9 passes substantially entirely through the plug, and an upper portion of it is guided in the guide sleeve 3, and a lower portion is guided in a bridge piece 10 inserted in the lower end of the tube 7. The stem 9 carries a valve 11, located in a chamber 12 formed in the body below the valve seat 2. Desirably the valve has a beveled active face 13 cooperating with a similarly beveled face of the seat to insure a tight fit when the valve is closed.

The valve is urged to close by one or more springs, such as an upper spring 14 located 55 about guide sleeve 3 and engaging a nut 15 screwed on the upper end of the valve stem and a lower spring 16 located about a lower portion of the stem and engaging against the bridge or guide piece 10 and a flange or washer 17 secured to stem 9. Either spring 90 may be dispensed with in some cases, and the precise location of the springs is not essential in a broader aspect of the invention.

Normally the valve is held open by means, such as a head 18, located in the upper end 95 of the body and secured to the body by a pin 19 passing through holes in ears 20 formed on the upper end of the body and a corresponding hole in the head 18. The head 18 may conveniently be designed for insertion in the ordinary drill stem or any lowering or hoisting member of well drilling apparatus, and for this purpose may be provided with a screw-threaded shank 21. The rod or pin 19 may vary in size and 100 strength, as sufficiently explained hereafter. In one particular case it is desirable to have it of a rather small diameter and of more or less easily breakable material, such as soft iron or a piece of ordinary iron wire.

The body is provided with expansive gripping members 25, the exact form and mode of operation of which may vary considerably. In the present case the members 25 are wedge pieces having part-cylindrical outer surfaces provided with teeth 26 directed upwardly and having beveled flat inner surfaces 27 engaging beveled surfaces 28 in the head, so that when the jaw members 25 slide downward in relation to the head they engage and grip a well casing or other tube into which the appliance is inserted, but when the gripping members are retained in upward position, as shown in Fig. 2, there is no gripping engagement with the casing. The members 25 are slidably secured by keys 29 moving in slots 30, centrally located in the body faces 28. These keys may be integral or separate and secured by screws 31, and they have flared inward edges 32 to prevent outward displacement of the jaws or grippers 26.

Where the appliance is to be used as a plug the connection at the point 19 is of a breakable nature, as above explained, and the valve mechanism is in place and retained in open position, as above described, by the head 18. As the tool is lowered into the casing the jaw members 26 ride up freely as just above described, and any oil or other liquid or gas in the casing is permitted to flow upward freely through the hollow interior of the tool as the tool descends, passing around the valve head 11 and through the apertures 5 and out at the upper end where ample space is provided at the sides of the ears 20. There is thus no substantial impediment to the ready lowering of the appliance to the desired position. When that point is reached the lowering rope is pulled up moderately to produce an initial engagement of the jaws 25 with the casing and then a much harder pull is applied, which first seats the jaw teeth still more firmly in the casing and then breaks the pin 19, releasing the lowering or hoisting means, including the head 18, and leaving the plug in the casing, and at the same time the withdrawal of the head 18 releases the valve stem which is moved up by its spring or springs and the valve is closed, thus cutting off any upward passage of liquid or gas and substantially sealing the casing.

Since it is desirable to make the maximum outside diameter of the appliance slightly less than the inner diameter of the casing to insure free movement of the tool to position, it is desirable in many cases to provide additional sealing means to insure the complete sealing of the space between the outside of the tool and the inside of the casing. Such means is provided in the present instance as follows: A long cylindrical sleeve or washer 40 of rubber, rubber composition or other suitable material, is located about

the tube 7 and has one end confronting a shoulder 41, formed by the lower end of the body 1 and the other end is engaged by a ring or washer 42 slidably mounted on the tube 7. The ring 42 is acted upon by a helical spring 43 of substantial strength, the spring being compressed between the ring 42 and a washer 44 which is held on the lower end of tube 7 by a locking ring 45. Normally the slidable ring 42 is held down so that the spring is compressed and the packing sleeve 40 is relieved of any compression effect by any suitable means, which in the present case cooperates with the valve stem as follows: The ring 42 is provided with an interior annular groove 46 engaged by one or more, usually a plurality, of pawls 47, pivoted in a body 48, which is secured to the valve stem. The pawls normally extend out through slots 49 in tube 7, sufficiently so that their outer corners 50 engage in the groove 46. The pawls are urged to this outer position by flat springs 51 bearing against inner edges of the pawls and carried by a sleeve or collar 52 secured to the valve stem 9.

Evidently so long as the valve stem is held down in the manner previously described, the pawls 47 are in position in engagement with the slidable ring 42 and the packing compressing spring 43 is kept from exerting any expansive effect upon the packing sleeve 40, which under the described conditions has its outer diameter slightly less than the inner diameter of the casing. The tool is then lowered in position, as above described, and when the valve stem is released by the breaking of pin 19 or in any other equivalent way, the upward movement of the valve stem retracts the pawls 47 inwardly and upwardly and the ring 42 is released and spring 43 moves the ring up against the lower end of the packing sleeve 40 and forcibly compresses the packing sleeve endwise, causing it to expand radially and form a tight and effective seal between the outside of the tool and the inner surface of the casing. There is thus provided a complete seal or closure at every point to prevent escape of the well contents. In some cases after the plug is located, cement may be poured into the hole to make a more permanent seal, but in many cases this is unnecessary and may be considered more in the nature of an added precaution.

What I claim is:—

1. In an appliance of the class described, a substantially hollow body, lowering means, an internal valve seat and a cooperating valve, and means for closing the valve when the lowering means is disconnected, the lowering means being arranged when in active position to definitely prevent valve closing.
2. In a well tool of the class described, a

- substantially hollow body, casing gripping means thereon, lowering means for the tool, an internal valve seat and a cooperating valve, and means for closing the valve when the lowering connection is disconnected, the lowering means being arranged when in active position to definitely prevent valve closing.
3. In a well tool of the class described, a substantially tubular main structure or body having a valve seat, a valve cooperating with the seat, spring means urging the valve to close, and a disconnectible lowering connection engaging the valve stem and positively retaining the vale open and acting to release the stem and permit closing of the valve when said connection is disconnected.
4. In a well tool of the class described, a substantially tubular main structure or body having a valve seat, a valve stem arranged for longitudinal movement in the body and having a valve to cooperate with the seat, spring means urging the valve to close, a lowering device engaging the valve stem and positively retaining the valve open and acting to release the stem and permit closing of the valve when said device is removed, and a breakable connection between said lowering device and the body.
5. In a well tool of the class described, a substantially tubular main structure or body having a valve seat, a valve cooperating with the seat, spring means urging the valve to close, a lowering connection disconnectible engaging the body and also engaging the valve stem and retaining the valve open and acting to release the stem and permit closing of the valve when said connection is disconnected, and casing gripping means on said body actuated by upward movement of the body.
6. In a well tool of the class described, a substantially tubular main structure or body having a valve seat, a valve stem arranged for longitudinal movement in the body and having a valve to cooperate with the seat, spring means urging the valve to close, a lowering device engaging the valve stem and retaining the valve open and acting to release the stem and permit closing of the valve when said device is removed, a breakable connection between said lowering device and the body, and casing gripping means on said body actuated by upward movement of the body.
7. A well appliance of the class described, comprising a main plug or body structure, casing gripping means thereon, a lowering connection disconnectible engaged with the body, an exterior packing, and means for expanding the packing in engagement with the casing after the tool is located at a desired point in the casing.
8. A well tool appliance of the class de- scribed, comprising a main plug or body structure, casing gripping means thereon, a valve seat and valve, a lowering connection, an exterior packing, and means actively tending to expand the packing in engagement with the casing after the tool is located at a desired point in the casing.
9. A well appliance of the class described, comprising a main plug or body structure, casing gripping means thereon, a lowering connection, an exterior packing, and means for expanding the packing in engagement with the casing when the lowering connection is disconnected, the lowering connection serving while in normal position to prevent operation of the packing expanding means.
10. A well appliance of the class described, comprising a main plug or body structure, casing gripping means thereon, a valve seat and valve, a lowering connection, an exterior packing, and means for expanding the packing in engagement with the casing when the lowering connection is disconnected, the lowering connection serving while in normal position to prevent operation of the packing expanding means.
11. A well appliance of the class described, comprising a main plug or body structure, casing gripping means thereon, a compressible and expansible packing sleeve on the exterior of the appliance, a spring to compress the packing sleeve longitudinally and expand it radially, means for holding the spring inactive, a lowering connection for the tool, and means acting upon disconnection of the lowering connection to retract said spring holding means and permit the spring to expand the packing sleeve.
12. A well appliance of the class described, comprising a main plug or body structure, casing gripping means thereon, a compressible and expansible packing sleeve on the exterior of the appliance, a spring to compress the packing sleeve and expand it radially, means for holding the spring compressed and inactive, a breakable lowering connection for the tool, and means acting upon breaking of the lowering connection to retract said spring holding means and permit the spring to expand the packing sleeve.
13. A well tool of the class described comprising a substantially hollow body having a valve seat, a valve, means urging the valve to close, a disconnectible lowering connection arranged to maintain the valve open, a packing member, means for operating the packing member, and means for holding said packing operating means inactive while the valve is held open.
14. A well tool of the class described comprising a substantially tubular body having a valve seat, a movable valve, spring means urging the valve to close, a lowering

connection including a breakable member and arranged to maintain the valve open, a packing member, means for operating the packing member, and means for holding 5 said packing operating means inactive while the valve is held open.

15. A well appliance of the class described, comprising a substantially tubular upper body portion, a lower tubular member extending from the body, the body being provided with a valve seat, a valve stem movable longitudinally in the body and tubular member, guide means for the valve stem, a valve on the stem cooperating with 15 the seat, spring means acting on the valve stem to close the valve, a disconnectible lowering member, the member normally engaging the valve stem and holding the valve open, casing gripping means on the body, a 20 packing sleeve located on said tubular member, a spring to expand the packing sleeve, means to retain the spring inactive, and means acting upon movement of the valve stem to withdraw the spring retaining 25 means.

16. A well appliance of the class described, comprising a substantially tubular upper body portion, a lower tubular member extending from the body, the body being provided with a valve seat, a valve stem 30 movable longitudinally in the body and tubular member, upper and lower guides for the valve stem, a valve on the stem cooperating with the seat, spring means acting on the valve stem to close the valve, a lowering 35 member, a breakable pin securing the member to the body, the member normally engaging the valve stem and holding the valve open, casing gripping means on the body, a packing sleeve located on said tubular 40 member, a spring to compress and expand the packing sleeve, means to retain the spring inactive, and means acting upon movement of the valve to withdraw the spring retaining means. 45

Signed at American consulate, Tampico, Mexico, this 11th day of September, A. D. 1922.

BENJAMIN EUGENE PARRISH.
